WHEELED GUN CARRIAGE

Nicolas Emilian Methlin, Paris, France, assignor
to Schneider & Cie, Paris, France, a company
of France

Application December 13, 1933, Serial No. 702,254
In France September 7, 1931

18 Claims. (Cl. 39—40)

The present invention relates to a wheeled gun carriage with split trail and one or more auxiliary trails as well as detachable wheels or an oscillating or non-oscillating set of wheels for 5 rapid conversion into an anti-aircraft gun carriage.

The gun carriage according to the invention is characterized by a system of trail legs so adapted that the said trail legs may both be brought simultaneously, either by individual or coupled action, alternatively into a position with the head raised in which the system of the said trail legs is arranged for traveling or for normal firing on wheels, or into a position with the head lowered 15 in which the oscillating gun and cradle, during the pivoting of the top carriage, can pass above the system of trail legs for firing at aerial objectives.

In order to be able to effect the change-over of 20 the trail legs from the position with the head raised into the position with the head lowered according to the invention, a construction may be provided in which the trail legs are acted upon individually, or both trail legs are acted upon together, the latter being adapted to slide separately or conjointly in the pintle bearing or carriage body when the carriage comprises an oscillating axle. When the carriage does not comprise an oscillating axle, the legs of the split trail being 25 in this case pivoted to a cross-piece adapted to oscillate in the pintle bearing rigidly supported by the axle, the changeover from the raised position to the lowered position may also be effected by pivoting the system of trail legs about the pivot 30 joining the cross-piece to the carriage body, or a cross-piece in two parts may be employed which parts are adapted to occupy two positions, one in which they raise the heads of the trail legs pivoted to their free ends and the other in which they lower them. Finally, particularly in the 35 case in which the carriage is not provided with an oscillating axle, the change-over from the raised position to the lowered position may be effected by a displacement of the longitudinal joint 40 of the system of trail legs in the pintle bearing, or there may be provided for the longitudinal joint of the system of trail legs a movable bearing adapted to be brought alternatively into an upper position or into a lower position, for example by means of a screw and nut mechanism. The first of these various constructional forms, which are merely cited by way of example, are represented in the accompanying drawings, the others being disclosed and claimed in my copending application Serial No. 620,272, filed June 30,

1932, of which this application is a continuation in part.

Figures 1 and 2 show respectively in side elevation and plan a constructional form of the invention employed in combination with equipment on wheels comprising an oscillating axle, and wherein in the legs of the split trail may be brought individually, by sliding of their heads, alternatively into the raised and lowered positions.

Figure 3 is a horizontal sectional view taken substantially on line 3—3 of Figure 1.

Figure 4 is a fragmentary elevation of a modification of the embodiment shown in Figures 1—3.

Figures 5 and 6 are side elevation and plan views of a portion of another gun mount embodying another form of the invention.

Figure 7 is a sectional end elevation taken substantially on line 7—7 of Figure 6.

The equipment itself may be of any known construction. It may comprise for example an oscillating mass, gun 1 adapted to recoil on a cradle 2, the latter being adapted to oscillate by means of trunnions 3 in a top carriage $a—a^1$ for elevation, the said top carriage in turn being adapted to pivot in a carriage body or a pintle bearing b , 20 a longitudinal joint c^2 permitting a transverse oscillation of the set of wheels $c^1—c—c^1$ relatively to an intermediate piece c^3 carried by the pintle bearing b , due to an attachment b^1 by means whereof the entire set of wheels may be 30 detached from the pintle bearing by horizontal sliding. The bottom carriage comprises two trail legs d, d , which for the purpose of being spread out and brought together are movable about pivots e, e which in the known equipments are 35 formed on or carried by the pintle bearing b .

According to the invention, the pivots e are each carried on an intermediate piece or trail leg head f which is adapted to slide on a curved guide b^2 , the section of which is clearly visible in Figure 3. The fixing of the trail legs in the bottom position is shown in full lines in Figure 1. By withdrawing the pin d^1 , the trail leg may be raised from the lowered position into the position for traveling or firing on wheels, the trail leg then being fixed by means of the pin d^1 engaging a second hole situated at a suitable level on the pintle bearing as indicated in chain lines in Figure 1. The guide b^2 , as shown in Figure 1, lies in a substantially vertical plane and is given a curved or arcuate shape such that its geometrical center lies in the immediate vicinity of the foot g of the trail leg.

In the example shown, the equipment also comprises a detachable auxiliary trail h , in one

or more parts, which is adapted to be fixed to the pintle bearing b for example by means of pins i , and at the same time to be connected to the trail legs d when the latter are in their lowered position. For this purpose, the auxiliary trail may comprise forks h^1 , as shown in elevation in Figure 1 and in plan in Figure 2, which, when the legs of the split trail are in their desired spread-out position for battery position 10 for firing against aerial objectives, engage corresponding bosses d^2 carried by the heads j of the said trail legs d and are secured thereto by pins h^2 . With the equipment which has just been described, the legs d of the split trail may 15 be brought together into the position with raised head for traveling, as indicated in chain lines in Figures 1 and 2. Of course, for traveling, the auxiliary trail will have to be removed and transported separately. In case of surprise, firing 20 may be carried out with the trail legs brought together and anchored to the ground in the position indicated in chain lines in Figure 1.

By leaving the trail legs in the raised position shown in Figure 1, firing may be effected 25 with the trail legs spread apart in a position of spread only limited by the wheels. Finally, in order to convert the equipment with a view to firing against aerial objectives, the heads of the trail legs are brought into the lower position 30 and the trail legs may then be spread further apart.

In order to convert the equipment definitely for firing against aerial objectives, an auxiliary trail h will be placed in position and the set of 35 wheels will then be removed. As shown in chain lines in Figure 1, the oscillating gun and cradle in all positions of elevation can pass above the trails, the pivoting of the gun and cradle in the pintle bearing b and the recoil of the gun 40 on the cradle being possible throughout the whole field of fire of 360° .

Figure 4 shows a modification of the device shown in Figures 1, 2 and 3. In this example, the guide provided for each of the trail leg heads 45 on the pintle bearing b is in the form of a rack b^3 for a pinion or a worm d^3 journaled in the trail leg head and adapted to be manipulated by a hand wheel or handle or ratchet. As in the case of guides b^2 , the centers of curvature of 50 arcuate racks b^3 are substantially coincident with the points of engagement of the trail leg feet g with the ground, and said racks lie in substantially vertical planes.

Figures 5 to 7 show respectively in side elevation, part plan, and part sectional end elevation, another constructional example comprising 55 a carriage with an oscillating axle.

In this example, the pintle bearing b comprises, for each of the heads of the legs d of the split trail, a substantially vertical helical guide b^4 60 which may be formed as a projection on the body of the pintle bearing b as shown in Figure 6 and which is engaged by the corresponding trail leg head. In the case in which the trail leg body d is rigidly integral with the head engaging the guide, the trail legs are capable of assuming exactly two positions, as indicated in full lines and chain lines respectively in Figures 5 and 6. When the trail legs occupy the upper position 65 at the top of the guides b^4 , they will necessarily be together for the purpose of limbering up and transport. When the trail legs occupy the bottom position indicated in full lines, they will necessarily be at the desired spread for 70 the battery position of the equipment, with

wheels removed, for firing against aerial objectives, or with a view to firing on the oscillating axle for ordinary field firing. Of course, it is possible in addition to provide heads of split trail legs guided helically on the pintle bearing b , the trail leg bodies being hinged to the said heads by vertical pivots, as in the embodiments of Figures 1-4. In this case, it would be possible to give any desired positions of spread to the trail legs. 10

The equipment may comprise, as shown in Figures 5 and 6, an auxiliary trail h , the head of which will be guided on segments b^5 provided on the pintle bearing b . Thus, by sliding the head on the guide, this trail may be brought into 15 the traveling position shown in chain lines in Figure 5, in which the trail body will be hooked underneath the cradle by a link $2'$. In the bottom position, the trail h may be fastened to the trail legs d , the latter carrying for this purpose lugs or bosses d^2 which are secured to the forks h^1 of the auxiliary trail head by pins h^2 . 20

What is claimed is:

1. In a gun carriage, a pintle bearing, a trail leg adapted to be secured to said bearing, and means for securing said trail leg to said bearing in a plurality of different positions relative thereto including a curved slide guide carried by said bearing, and a cooperating slide block member secured to said trail leg and engaging said guide in sliding relation therewith, said guide being so constructed and arranged that when said slide block member is adjacent the upper and lower ends of said guide the trail leg is in raised position for normal firing with the gun transportation means in place and lowered emplaced position for firing at aerial objectives, respectively. 30

2. In a gun carriage, a pintle bearing, a trail leg adapted to be secured to said bearing, and means for securing said trail leg to said bearing in a plurality of different positions relative thereto including a curved slide guide carried by 40

said bearing and having its center of curvature substantially coincident with the point of engagement of said trail leg with the ground, and a cooperating slide block member secured to said trail leg and engaging said guide in sliding relation therewith, said guide being so constructed and arranged that when said slide block member is adjacent the upper and lower ends of said guide the trail leg is in raised position for normal firing with the gun transportation means in place and lowered emplaced position for firing at aerial objectives, respectively. 45

3. In a gun carriage, a pintle bearing, a trail leg adapted to be secured to said bearing, and means for securing said trail leg to said bearing in a plurality of different positions relative thereto including a curved slide guide carried by 50

said bearing, a cooperating slide block member secured to said trail leg and engaging said guide in sliding relation therewith, said guide being so constructed and arranged that when said slide block member is adjacent the upper and lower ends of said guide the trail leg is in raised position for normal firing with the gun transportation means in place and lowered emplaced position for firing at aerial objectives, respectively, an auxiliary trail, and means for connecting said auxiliary trail to a portion of the gun carriage 55 that is fixed during firing when the trail leg is in lowered position. 60

4. In a gun carriage, a pintle bearing, a split trail having a pair of legs adapted to be secured to said bearing, means for securing said trail legs 65

- to said bearing in raised and lowered positions including a pair of curved slide guides carried by said bearing and a cooperating slide block member carried by the inner end of each of said legs and engaging one of said guides in sliding relation therewith, said guides being so constructed and arranged that when said slide blocks are adjacent the upper and lower ends of said guides the trail legs are in raised position for 5 normal firing with the gun transportation means in place and lowered emplaced position for firing at aerial objectives, respectively, an auxiliary trail and means for connecting said auxiliary trail to a portion of the gun carriage that is fixed 10 during firing when said split trail legs are in lowered position.
5. In a gun carriage, a pintle bearing, a split trail having a pair of legs adapted to be secured to said bearing, means for securing said trail legs to said bearing in raised and lowered positions including a pair of curved slide guides carried by said bearing and a cooperating slide block member carried by the inner end of each of said legs and engaging one of said guides in sliding relation 15 therewith, said guides being so constructed and arranged that when said slide blocks are adjacent the upper and lower ends of said guides the trail legs are in raised position for normal firing with the gun transportation means in place and lowered emplaced position for firing at aerial objectives, respectively, an auxiliary trail; and means for connecting said auxiliary trail to both said pintle bearing and said split trail legs when the latter are in lowered position.
- 35 6. In a gun carriage, a pintle bearing, a split trail having a pair of legs adapted to be secured to said bearing, means for securing said trail legs to said bearing in raised and lowered positions including a pair of curved slide guides carried 40 by said bearing and a cooperating slide block member carried by the inner end of each of said legs and engaging one of said guides in sliding relation therewith, said guides being so constructed and arranged that when said slide blocks are adjacent the upper and lower ends of said guides the trail legs are in raised position for normal firing with the gun transportation means in place and lowered emplaced position for firing at aerial objectives, respectively, an auxiliary trail having a forked trail head, and means for connecting said forked trail head to the slide block members of said split trail legs when the latter are in lowered position.
- 45 7. In a gun carriage, a pintle bearing, a trail leg adapted to be secured to said bearing, and means for securing said trail leg to said bearing in a plurality of different positions relative thereto including a slide guide carried by said bearing, an intermediate member engaging said guide and adapted to slide thereon, and a pivotal connection between said intermediate member and said trail leg.
8. In a gun carriage, a pintle bearing, a trail leg adapted to be secured to said bearing, and means for securing said trail leg to said bearing in a plurality of different positions relative thereto including a substantially vertical slide guide carried by said bearing, an intermediate member engaging said guide and adapted to slide up and down therealong, and a pivotal connection having a substantially vertical axis between said intermediate member and said trail leg.
9. In a gun carriage, a pintle bearing, a trail leg adapted to be secured to said bearing, and means for securing said trail leg to said bearing in a plurality of different positions relative thereto including an arcuate slide guide carried by said bearing and having its center of curvature substantially coincidental with the point of engagement of said trail leg with the ground, an intermediate member engaging said guide and adapted to slide therealong, and a pivotal connection between said intermediate member and said trail leg.
10. In a gun carriage, a pintle bearing, a trail leg adapted to be secured to said bearing, and means for securing said trail leg to said bearing in a plurality of different positions relative thereto including a substantially vertical arcuate slide guide carried by said bearing and having its center of curvature substantially coincidental with the point of engagement of said trail leg with the ground, an intermediate member engaging said guide and adapted to slide up and down therealong, means for locking said intermediate member in a plurality of positions relative to said guide, and a pivotal connection having a substantially vertical axis between said intermediate member and said trail leg.
- 15 11. In a gun carriage, a pintle bearing, a trail leg adapted to be secured to said bearing, and means for securing said trail leg to said bearing in a plurality of different positions relative thereto including a slide guide carried by said bearing and provided with teeth constituting a rack, an intermediate member engaging said rack and carrying a pinion adapted to roll along said rack, and a pivotal connection between said intermediate member and said trail leg.
- 20 12. In a gun carriage, a pintle bearing, a trail leg adapted to be secured to said bearing, and means for securing said trail leg to said bearing in a plurality of different positions relative thereto including a substantially vertical slide guide carried by said bearing and provided with teeth constituting a rack, an intermediate member engaging said guide and carrying a pinion adapted to roll up and down along said rack, and a pivotal connection having a substantially vertical axis between said intermediate member and said trail leg.
- 25 13. In a gun carriage, a pintle bearing, a trail leg adapted to be secured to said bearing, and means for securing said trail leg to said bearing in a plurality of different positions relative thereto including a curved slide guide carried by said bearing and provided with teeth constituting a rack, the center of curvature of said guide being substantially coincidental with the point of engagement of said trail leg with the ground, an intermediate member engaging said guide and carrying a pinion adapted to roll up and down along said rack, and a pivotal connection between said intermediate member and said trail leg.
- 30 14. In a gun carriage, a pintle bearing, a split trail having a pair of legs adapted to be secured to said bearing, and means for securing said trail legs to said bearing in raised and lowered positions including a pair of helical slide guides carried by said bearing, and a slide block carried by the inner end of each of said trail legs and engaging one of said guides, said guides being so constructed and arranged that when said slide blocks are adjacent the upper and lower ends of said guides the trail legs are in raised position for normal firing with the gun transportation means in place and lowered emplaced position for firing at aerial objectives, respectively.
- 35 15. In a gun carriage, a pintle bearing, a split trail having a pair of legs adapted to be secured to said bearing, and means for securing said trail legs to said bearing in a plurality of different positions relative thereto including a curved slide guide carried by said bearing and provided with teeth constituting a rack, the center of curvature of said guide being substantially coincidental with the point of engagement of said trail leg with the ground, an intermediate member engaging said guide and carrying a pinion adapted to roll up and down along said rack, and a pivotal connection between said intermediate member and said trail leg.

- to said bearing, and means for securing said trail legs to said bearing in raised and lowered positions including a pair of helical slide guides carried by said bearing, the upper ends of said guides being closer together than the lower ends, and a slide block formed integrally with the inner end of each of said trail legs and engaging one of said guides, said guides being so constructed and arranged that when said slide blocks are adjacent the upper and lower ends of said guides the trail legs are in raised position for normal firing with the gun transportation means in place and lowered emplaced position for firing at aerial objectives, respectively, an auxiliary trail, slide means carried by said bearing for guiding the movement of said auxiliary trail to and from raised and lowered positions, and means for connecting said auxiliary trail to said split trail legs when in lowered position.
- 5
15. In a gun carriage, a pintle bearing, a split trail having a pair of legs adapted to be secured to said bearing, means for securing said trail legs to said bearing in raised and lowered positions including a pair of helical slide guides carried by said bearing, and a slide block carried by the inner end of each of said trail legs and engaging one of said guides, said guides being so constructed and arranged that when said slide blocks are adjacent the upper and lower ends of said guides the trail legs are in raised position for normal firing with the gun transportation means in place and lowered emplaced position for firing at aerial objectives, respectively, an auxiliary trail, slide means carried by said bearing for guiding the movement of said auxiliary trail to and from raised and lowered positions, and means for connecting said auxiliary trail to said split trail legs when in lowered position.
